(57) **CLAIM**

The ornamental design for a reagent cassette, as shown and described.

DESCRIPTION

FIG. 1 is a perspective view of the front and right side of a reagent cassette in an open position showing our new design;

FIG. 2 is a perspective view of the rear and left side thereof; FIG. 3 is a perspective view of the front and right side of the reagent cassette in a closed position;

FIG. 4 is a perspective view of the rear and left side thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a rear elevational view thereof; and,

FIG. 10 is a front elevational view thereof.

The broken lines in the Figs. depict environmental subject matter and form no part of the claimed design.
